UNITED STATES PATENT OFFICE.

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed September 27, 1923. Serial No. 665,134.

This invention relates to fastening inserting machines and is disclosed herein as embodied in a metallic fastening inserting machine of a type used in the manufacture of 5 boots and shoes.

Many of the machines used to insert nails, tacks and the like in the manufacture of boots and shoes are provided with driver operating mechanism comprising a driver 10 bar to the lower end of which the driver is clamped, a stiff spring connected to the upper end of the driver bar and tending to force the driver bar downwardly, a rotating cam adjacent to the driver bar and a lifting 15 block carried by the driver bar, the cam cooperating with the lifting block to elevate the driver bar against the action of the spring, so that when the cam passes out of engagement with the lifting block the driver 20 bar and driver will be forced downwardly by the spring to drive the nail or other fastening into the work.

It has been found that the driver bars of machines of this type frequently break, there 25 being no ascertainable cause for the failure of the driver bar except that condition of "fatigue" commonly spoken of as "crystallization" resulting from the long continued series of shocks to which the driver bar has 30 been subjected.

It is an object of the present invention to prolong the lives of the driver bars of such machines by reducing, so far as possible, the shock to which the driver bars are subjected. 35 With this in view, a feature of the invention comprises a resilient lifting block which is attached to the driver bar of the machine in place of the rigid block heretofore used, the resilient lifting block being located in the 40 path of movement of the lifting cam so that the shock of the blow of the lifting cam upon the lifting block is cushioned and "fatigue" or "crystallization" of the driver bar is thereby avoided.

45 With the above and other objects and features in view, the invention will now be described in connection with the accompanying drawings and pointed out in the claims.

In the drawings,

50 Fig. 1 is a front elevation, with certain parts in section of the head of a fastening inserting machine embodying the present invention;

Fig. 2 is a perspective view of the driver

bar with a novel lifting block attached thereto and showing the relation of the latter to a wear plate carried by the head of the machine; and

Fig. 3 is a perspective view of the resilient lifting block detached from the machine.

The invention is herein disclosed as embodied in a tacker of the type more fully shown in United States Letters Patent No. 910,147, granted January 19, 1909, on an application of Frederick H. Perry. Since machines of this type are well known in the art, it is believed that a very brief description of the general organization of the machine will suffice, and that it is not necessary to set forth in detail the construction thereof 70 since reference may be had to said Letters Patent for that information.

The illustrated machine is provided with a column 6 carrying a head 8 upon which is supported a reel 10 to carry a coil of wire 12. Fastenings are cut from the wire 12 and fed to nozzle 14 of the machine by appropriate mechanism which may be and is illustrated as substantially like that disclosed in said Letters Patent No. 910,147.

The head 8 of the machine is provided with bearings for a cam shaft 16 operated and controlled in any suitable manner and carrying a cam 18 provided with an elevated portion terminating in a toe 20 arranged to cooperate with lifting block 22 carried by the driver bar 24 to the lower end of which is clamped the driver 26. The upper end of the driver bar 24 is connected by a link 28 to one end of a lever 29 to which is secured one end of a stiff torsion spring 30, the other end of which is anchored to head 8 of the machine. As cam 18 rotates, its toe 20 engages lifting block 22 and forces it upwardly thus elevating driver bar 24 and driver 26 and tensioning spring 30. When the elevated portion of cam 18 passes beyond lifting block 22, the driver bar and driver are forced downwardly by spring 30 thus driving the fastening into the work.

It has been found that the repeated shock to which the driver bar is subjected by this mode of operation induces in the driver bars that condition of "fatigue" commonly spoken of as "crystallization," with the result that the driver bars break after they have been used for a period of time, and this breakage has not been overcome by the

cushioning effect provided by leather washers 30 backed up by a collar 32 carried by driver bar 24 and co-operating at the downward extremity of the path of movement of the driver bar with a stop 34 carried by the head of the machine.

In order to cushion the shock of the blows struck by the toe 20 of lifting cam 18 when the toe contacts with the lifting block, I have made the latter of a resilient construction. As herein disclosed the lifting block comprises a heavy bow spring having a U-shaped portion consisting of two arms 36, 38 (Figs. 2 and 3), arm 38 being extended beyond the extremity of arm 36, thickened at 40 and bent at right angles at 42 to provide a downwardly extending portion 44. The thickened portion 40 of the lifting block is perforated at 46 so that it may be clamped to the driver bar as by nuts 48 (Fig. 1). The bent portion 44 engages a flat 50 formed upon the driver bar 24 and also provides a wear surface having sliding engagement with a wear block 52 adjustably mounted as by a bolt and slot connection 54 upon the head of the machine. With this construction not only is the shock of the lifting cam upon the lifting block cushioned so that fatigue of the driver bar is avoided but also the slack may be easily taken up as the contacting surfaces of the lifting block and the wear plate wear so that these parts of the machine may be kept in a smooth running condition and vibration avoided. This lifting block, moreover, is inexpensive to manufacture and may be replaced when necessary with a minimum of effort.

While the invention has been disclosed herein as embodied in a machine of the type disclosed in said Letters Patent, No. 910,147, it should be understood that the invention is in no way limited to a machine such as is shown in said Letters Patent since evidently it is applicable also to other machines.

Having described the invention, what I claim as new and desire to secure by Letters Patent of the United States is:—

1. A lifting block for fastening inserting

machines comprising a stiff spring having a U-shaped portion with one of the arms of the U longer than the other and bent substantially at right angles to provide means for securing the block to the driver bar of a fastening inserting machine.

2. A lifting block for fastening inserting machines comprising a bow spring arranged to have one of its extremities secured to the driver bar of a fastening inserting machine and to be engaged toward its other extremity by the lifting cam of the machine.

3. A lifting block for fastening inserting machines consisting of a stiff spring arranged to be secured to the driver bar of the machine directly to receive the blows of the lifting cam of the machine.

4. A lifting block arranged to be secured to the driver bar of a fastening inserting machine and to be engaged by the lifting cam of the machine to lift the driver bar, characterized by the fact that the block is of a resilient construction so as to cushion the blows of the lifting cam against the block.

5. A fastening inserting machine having, in combination, a driver bar, a lifting cam, a resilient lifting block attached to the driver bar and positioned in the path of movement of the lifting cam to cause the latter to elevate the driver bar, and a spring connected to the driver bar and compressed by the lifting thereof so as to force the driver bar down when the lifting cam passes from beneath the lifting block.

6. A fastening inserting machine having a driver bar, a lifting cam, a spring lifting block attached to the driver bar and projecting into the path of movement of the lifting cam to cause the latter to lift the driver bar, means for forcing the driver bar down when the cam passes out of engagement with the lifting block, and an adjustable wear plate engaging the lifting block during the reciprocation of the driver bar.

In testimony whereof I have signed my name to this specification.

GEORGE GODDU.
